UNITED STATES PATENT OFFICE.

SAMUEL L. ADLER, OF STONEWALL, MISSISSIPPI, ASSIGNOR OF ONE-FOURTH TO
MARION A. GILLELAND, OF STONEWALL, MISSISSIPPI.

RAILWAY-SIGNAL.

1,004,131.

Specification of Letters Patent. Patented Sept. 26, 1911.

Application filed March 25, 1910. Serial No. 551,505.

To all whom it may concern:

Be it known that I, SAMUEL L. ADLER, a citizen of the United States, residing at Stonewall, in the county of Clarke and State 5 of Mississippi, have invented a new and useful Railway-Signal, of which the following is a specification.

It is the object of this invention to provide a railway signal of novel and improved 0 form, to provide a means for mounting the signal, so that it may be swung pendulum-wise or restrained against swinging, and to provide a novel mechanism for operating the signal.

Another object of the invention is to provide a novel means for actuating the operating mechanism, and to provide novel means for operatively uniting the several constituent 5 mechanisms of the device.

The drawings show but one form of the invention, and it is to be understood that changes, properly falling within the scope of what is claimed, may be made, without departing from the spirit of the invention.

In the drawings,—Figure 1 is a side elevation of the complete device, parts being broken away; Fig. 2 is a side elevation of the signal and of the mechanism whereby the same is operated, the housing for the operating mechanism being entirely removed, in order that structural details may more clearly appear; Fig. 3 is a side elevation, partly in section, showing a yieldable connecting rod which enters into the structure; Fig. 4 is a transverse section of the signal-proper, and of a portion of the housing whereby the signal-proper is carried, parts being shown in elevation; Fig. 5 is a transverse section of the signal-proper and its mounting, the cutting plane being at right angles to the cutting plane of Fig. 4; Fig. 6 is a top plan of the signal-proper, parts being broken away; Fig. 7 is a transverse section of the signal, the cutting plane being at right angles to the cutting planes of Figs. 4 and 5; and Fig. 8 is a fragmental perspective, depicting certain details of the operating mechanism.

The device forming the subject matter of this application is adapted to be mounted adjacent railway tracks, in order to impart information to the operators of passing trains.

The device consists, broadly speaking, of

three constituent parts; a supporting structure; a signal; and a means for operating the signal.

The supporting structure and the general construction of the device will be briefly described first; the signal-proper will then be 60 described in detail; and finally the operating mechanism will likewise be described in detail.

The supporting structure consists of a box-like base or housing 1, from which rises a 65 vertical, tubular standard 2, a horizontal, tubular arm 3 being connected with the standard 2 by means of an elbow 4. Secured to the end of the arm 3 is a casing 5. A signal box 6 is suspended in the casing 5, 70 and so mounted therein that it may be swung to and fro, as shown in dotted lines in Fig. 1. The signal box 6 is protected by a hood 7 supported upon the arm 3. The signal is swung by means of an operating 75 mechanism located within the housing 1, suitable connections, located in the standard 2, in the elbow and in the arm 3, uniting the operating mechanism with the signal. An operating rod 8 protrudes from the base 80 of the housing 1. This operating rod serves to position the signal box 6 in such a way that it may be swung back and forth, and likewise constitutes a means for setting a motor 9 in operation, whereby the signal 85 box 6 may be swung. At this point, it may profitably be stated that the operating rod 8 may be actuated in any desired manner. If desired the operating rod may be connected with a switch point, with a movable 90 member of a switch stand or the like, the signal box 6 thus being put in motion when the switch point is thrown. However, the device may be used in connection with block signal systems, and in such case, the operating rod 8 may be thrown manually. So far as the operation of the structure as an entity is concerned, it is entirely immaterial what means are employed for manipulating the operating rod 8.

Passing now to a detailed description of the signal-proper, it will be seen that the signal box 6 is surmounted by a slanting top 10, terminating in a tubular neck 11. In this neck 11 are located spaced, perforated ventilating screens 12, of any desired construction.

The invention further includes a cruci-

100

105

2
form signal holder 14, the outline of which is seen to best advantage in Fig. 5. The lower, upright arm 15 of the signal holder is secured in the screens 12. The upper, up-right arm 16 of the signal holder is provided in its end with a socket 17. This socket 17 serves to receive a portion of the mechanism whereby the signal is operated; as will be made plain hereinafter. There is 10 an opening through the transverse arms 18 of the signal holder, and in this opening is mounted a shaft 19. The ends of the shaft 19 are mounted in a signal support, the same being shown in the form of a ring 20. 15 This ring 20 is adapted to be inserted in the bottom 21 of the casing 5, and about the periphery of the ring 20, at its upper end, there is an outstanding flange 22 which operates to hold the ring 20 against slipping 20 downwardly through the bottom 21 of the casing 5. If desired, an auxiliary ring 23 may be secured about the ring 20 below the bottom 21, thus securing the ring 20 in place in the bottom 21, for rotation in a fixed 25 horizontal plane.

In the four side walls of the signal box 6, there are bull's eye lenses. Two of these lenses, disposed opposite to each other, preferably show a white light, while the two other lenses, denoted by the numeral 25 show a red light; the white lenses being denoted by the numeral 24. The sides of the signal box 6 in which the red lenses 25 are located, are painted red; while those sides 30 of the box in which the white lenses are located, are painted white. When the track is clear, and the signal is in running position, a white side of the signal box and one of the white lenses 24 will be disposed toward a passing train. The signal is thus depicted in Fig. 1.

Located within the signal box 6 is a display element of some sort, the same being shown in the present instance, conventionally, in the form of a lamp 26, retained in place by a suitable holding device 27. Journaled for rotation in the signal box 6, and disposed at right angles to the planes of the red bull's eye lenses 25, is a shaft 28. Diverging display arms 29, terminating in enlarged disks 30 are secured to the shaft 28 adjacent the ends thereof, there being a set of these diverging arms 29 for each of the red bull's eye lenses 25.

55 A rigid connection 31 is pivotally united, eccentrically, with the shaft 28, the upper end of the connection 31 being pivotally united, as seen most clearly in Fig. 4, with the inner face of the ring 20. In the lower 60 upright arm 15 of the signal holder, there is a slot 68, adapted to receive the connection 31.

Passing now to a description of the mechanism whereby the signal is operated, it

will be seen, by referring to Fig. 2, that one 65 arm of a bell crank 32, pivotally supported at 33 in the housing 1, is connected pivotally to the operating rod 8. The lower end of a rod 34 is pivoted to the other arm of the bell crank 32. This rod 34 exercises 70 important functions in the operating mechanism, and for clearness, the rod 34 will be referred hereinafter as the actuating member.

Pivotally supported in the elbow 4, is a 75 bell crank 35, the lower end of which is pivotally connected to the upper end of the actuating member 34. A rod 36, disposed in the arm 3, is pivotally connected at one end to the upper arm of the bell crank 35 the 80 other end of the rod 36 being mounted for rotation in the upper surface of the ring 20.

In order to actuate the operating mechanism a motor 9 is provided. In the present instance, the motor 9 is electrically driven 85 and is located within the housing 1. This motor 9 actuates a worm shaft 37, the same meshing into a worm wheel 38 which is supported for rotation in the housing 1. A pitman 39 connects the worm wheel 38 with 90 an arcuate transverse head 40, located at the end of a rock arm 41, pivotally supported at 42 in the housing 1.

Upon the actuating member 34, there is a shoulder 43 adapted to engage one arm of a 95 bell crank 44, pivotally supported at 45 in the housing 1. The extremity of the other arm of the bell crank 44 is pivotally united with a yieldable connecting rod 46. This connecting rod 46 is shown in detail in Fig. 100 3, and it will there be seen that it comprises telescoped parts 47, united by a retractile spring 48, housed within the contour of the parts 47. An upright rod 49 is pivotally connected to one end of the element 46. The 105 pivotal union between the members 46 and 49 may be effected, as shown in Fig. 8, by a pivot pin 50. This pivot pin 50 outstands beyond the connecting member 46 and is adapted to be engaged in a notch 67 in the 110 head 40 of the arm 41. The upper end of the rod 49 is pivotally connected with one arm of a bell crank 51 which is mounted to swing in the elbow 4.

It will be seen that the rod 49 may be 115 tilted to and fro, and it will be described hereinafter under the general designation of a tiltable rod. When the pin 50 is engaged in the notch 67 of the head 40 of the rock arm 41 it will be seen that the rod 49 12 is operatively connected with the motor 9, and these interlocking elements upon the members 49 and 40 will be referred to hereinafter as a locking device for operatively connecting the tiltable rod 49 with the motor 9.

Pivotally connected with one arm of the bell crank 51, is a horizontally disposed rod

52, located in the arm 3. Hinged to the end of the rod 52 is a pin 53. As seen most clearly in Fig. 5, this pin 53 registers rotatably in the socket 17 of the signal holder.

5 A locking device is provided for holding the tiltable rod 49 in such a position that the pin 50 is out of engagement with the notch 67 in the head of the rock arm 41. This locking device includes a finger 54 which, at 10 one end is pivoted as shown at 55, within the housing 1. An upright arm 56 is pivoted at one end to the intermediate portion of the finger 54. The upper end of the arm 56 is pivoted to one end of a finger 57, the 15 finger 57 being pivotally supported, intermediate its ends, at 58, within the housing 1. Fixed upon the tiltable rod 49 is a shoulder 59, and this shoulder 59 is, as seen in Fig. 8, notched, to receive the free ends of 20 the fingers 54 and 57 and, when the fingers are thus in engagement with the shoulder 59, it will be seen that the tiltable rod 49 will be so held that the pin 50 cannot swing into engagement with the notch 67 in the 25 head 40 of the rock arm 41 when the rock arm is moved.

Fixed to the actuating member 34 and outstanding at right angles thereto, is an arm 60. A compression spring 61 surrounds the actuating member 34 beneath the arm 60, the compression spring abutting against the arm 60 at one end, and, at the other end, abutting against a washer 62, secured to the spring 61 and adapted to bear 35 upon the finger 57, intermediate its fulcrum 58 and that end of the finger which is in engagement with the shoulder 59. Upon the end of the arm 60 there is a transverse brush 63, adapted to wipe to and fro upon a contact plate 64, upheld in any suitable manner within the housing 1. This brush 63 is arranged to complete an electrical circuit through a conductor 65, united with the motor 9. The current for actuating the motor 45 9 may be supplied in any desired manner. In the present instance, in order to embody a concrete example, a battery 66 is shown located within the housing 1, but it is obvious that any other means for energizing the 50 motor 9 may be provided.

In Figs. 1 and 2 of the drawings, the several parts of the invention are shown in the positions which they will assume when one of the white bull's eyes 24 is disposed toward 55 an oncoming train, the signal thus indicating that the track is clear. Suppose, however, that, through the throwing of a switch point, or by means of a manually operated signal lever or the like, the operating rod 8 is moved in the direction of the arrow A in Fig. 2. Then the operation of the device 60 will be as follows. As the operating rod 8 moves in the direction of the arrow A, the actuating member 34 will, through the in-

strumentality of the bell crank 32, move in 65 the direction of the arrow B. As the actuating member 34 thus moves, the arm 60 will be lifted, causing the brush 63 to complete the circuit in the conductor 65, thus energizing the motor 9. As the actuating mem- 70 ber 34 moves in the direction of the arrow B, the rod 36 through the instrumentality of the bell crank 35, will move in the direction of the arrow C. By referring to Figs. 5 and 6 it will be seen that the transverse arms 18 of the signal holder 14 are normally disposed in a common plane with the rod 52 whereby the holder is tilted; but, when the rod 36 moves in the direction of the arrow C, the ring 20 will be rotated, positioning 75 the transverse arms 18 at right angles to the rod 52, thus positioning the signal in such a manner that it may be tilted by the rod 52 as hereinafter described. The movement of the actuating member 34 in the direction of 80 the arrow B, as described up to this point, has resulted in actuating the motor 9 and in turning the signal box 6 through an arc of 90°, so that it may be tilted to and fro as shown in dotted line in Fig. 1. The opera- 85 tion of tilting the signal box may now be set forth.

As soon as the motor 9 is put into operation, it will cause a rotation of the worm shaft 37, the worm shaft causing the arm 95 wheel 38 to rotate, the pitman 39 raising the head 40 of the rock arm 41. Obviously, so long as the motor 9 is in operation, the rock arm 41 will move upwardly and downwardly at its free end, upon the pivot point 100 42 of the rock arm.

When the actuating member 34 moves in the direction of the arrow B, carrying with it the arm 60, the spring 61 will be lifted, so that it no longer exerts a pressure upon the 105 finger 57. When this spring pressure is removed from the finger 57, the fingers 57 and 54 will drop apart at their free ends. This operation takes place by reason of the fact that the portion of the finger 54 which is located between the free end of the finger 54 and the point of union between the said finger and the arm 56, is sufficiently heavy to separate the fingers when the pressure of the spring 61 upon the arm 57 is removed. 110 When the free ends of the arms 57 and 54 are thus spaced apart, they will release the shoulder 59 of the tiltable rod 49.

As the actuating member 34 moves in the direction of the arrow B the shoulder 120 43 will engage the free end of the bell crank 44, tilting the bell crank, and causing the connecting rod 46 to draw the lower end of the tiltable rod 49 toward the head 40 of the rock arm 41. The pin 50 will, 125 through the instrumentality of the spring 48 (Fig. 3), be drawn against the edge of the head 40, the pin 50 ultimately regis-

tering in the notch 67 as the head 40 reciprocates. When the pin 50 is thus in engagement with the notch 67, the tilttable rod 49 will be operatively connected with the motor 9, so that, as the worm wheel 38 rotates, the rod 49 will reciprocate vertically. It should be recalled at this point, that in the initial movement of the actuating member 34, the ring 20 has been turned to an angle of 90° so that the transverse arms 18 of the signal holder now stand at right angles to the rod 52. Therefore, when the rod 49 reciprocates longitudinally, the rod 52, through the medium of the bell crank 51, will reciprocate longitudinally, causing the signal box 6 to swing to and fro as indicated in Fig. 1, so long as the motor 9 is in operation.

As the signal box swings to and fro, the connection 31, being secured at its upper end to the ring 20, will maintain the several display arms 29 in fixed positions, the disks 30 alternately occulting the lenses 25, as the said lenses swing past the disks 30. Thus, when the lamp 26 is lighted, the same will not only be swung back and forth, but, at the same time, will be made to flash, as it swings.

When the operating rod 8 is moved in the direction of the arrow D, the signal box 6 will be turned back through 90° into its original position, thus locking the swinging holder 14 against movement, the brush 63 breaking the circuit through the conductor 35 and stopping the motor 9. The shoulder 43 moving from beneath the bell crank 44, the lower arm of the same will drop, the connecting member 46 tilting the rod 49 and moving the pin 50 out of the slot 67 in the head 40. The spring 61 will be made to bear against upon the arm 57, closing the free ends of the arms 54 and 57 together upon the shoulder 59 of the tilttable rod 49 and engaging the same, as seen in Fig. 8; the several parts of the device thus being restored to the positions originally described, and depicted in Fig. 2.

Having thus described the invention, what is claimed is;

- 50 1. A device of the class described comprising a signal holder mounted for axial rotation and for swinging movement in a single plane shifting with the rotation of the holder; means operating in a fixed plane for swinging the holder; and means for rotating the holder to cause the plane of swinging movement of the holder to pass into and out of coincidence with the operating plane of the swinging means.
- 60 2. A device of the class described consisting of a ring held for rotation in a fixed plane; a cruciform signal holder having its transverse arms pivoted in the ring; means for rotating the ring; means for swinging

the holder; and a signal carried by the signal holder.

3. A device of the class described comprising a support; a signal box mounted for swinging movement in the support; a display element carried by the signal box; an arm pivotally carried by the signal box for movement in front of the display element; and a rigid connection between the arm and the support.

4. A device of the class described comprising a signal mounted for rotation and for swinging movement; an actuating member; a motor; means operable by the actuating member to start and to stop the motor; means connecting the motor with the signal to swing the signal; and means connecting the actuating member with the signal for rotating the signal.

5. A device of the class described comprising a signal; an actuating member; a motor; means operable by the actuating member to start and to stop the motor; means for swinging the signal; and a locking device operable by the actuating member for operatively connecting the swinging means with the motor.

6. A device of the class described comprising a signal mounted for swinging movement and for rotation; an actuating member constituting a means for rotating the signal; a tilttable rod arranged to swing the signal; a rock arm; means for operating the rock arm; a device upon the actuating member for starting and stopping the operating means; means operable by the actuating member for causing the tilttable rod to interlock with the rock arm; and a locking device operable by the actuating member to hold the tilttable rod out of engagement with the rock arm.

7. A device of the class described comprising a signal mounted for swinging movement and for rotation; an actuating member constituting a means for rotating the signal; a tilttable rod arranged to swing the signal; a finger pivotally supported at one end; a finger pivotally supported intermediate its ends; a connection between one end of the last named finger and the intermediate portion of the first named finger; means for causing the free ends of the fingers to interlock with the tilttable rod; a device for operating the tilttable rod; means for causing the tilttable rod to interlock with the operating means when the fingers are out of engagement with the rod; and an operative connection between the actuating member and the operating means to start and to stop the latter.

8. A device of the class described comprising a signal mounted for swinging movement; a bell crank; a connection between one arm of the bell crank and the signal;

a rod pivoted at one end to the other arm of the bell crank; a pivotally mounted rock arm arranged to be pivotally united with the last named rod; a worm wheel; a pitman connecting the worm wheel with the rock arm; a worm shaft engaging the worm wheel; and a motor for driving the worm shaft.

In testimony that I claim the foregoing as my own, I have hereto affixed my signature in the presence of two witnesses.
